CONTACT FOR ELECTROMAGNETIC MECHANISM.

1,048,670.

Specification of Letters Patent.

Patented Dec. 31, 1912.

Application filed March 16, 1906. Serial No. 306,387.

To all whom it may concern:

Be it known that I, REGINALD A. FESSENDEN, a citizen of the United States, and resident of Washington, District of Columbia, 5 have invented certain new and useful Improvements in Contacts for Electromagnetic Mechanism, of which the following is a specification.

The invention relates to electrical contacts, and is especially adapted for use in 10 sensitive relays.

Great difficulty has been experienced in the use of relays from the sparking and consequent welding together of the contacts, 15 even when a condenser is used across the contacts. And further the surfaces of the contacts become oxidized or otherwise deteriorated so that the pressure of one contact on the other is not sufficient to break or 20 destroy the resisting film and permit of the completion of the circuit.

My invention has for its object the prevention of a weld between contacts and the 25 rupture of such weld, if formed, without interference with the operation of the relay or other instrument.

It is a further object of the invention to prevent the formation of a non-conducting film on the surfaces of the contacts and its 30 removal or breaking up if formed, as hereinafter more fully described and claimed.

In the accompanying drawing forming a 35 part of this specification is shown diagrammatically a relay and circuits for operating a bell.

In the practice of my invention a finger 1 is attached to the movable part or member of a relay, as for example the movable coil 2 of the Weston type of relays. This finger 40 is preferably made so that it will bend or flex under slight pressure, and has sufficient resilience to return to normal position when relieved of the pressure. This finger is provided on one or both sides, dependent on the 45 use to which the relay is put, with contacts 3. Similar contact or contacts, 4, are secured to springs or yielding members, 5 and 6, adapted to yield readily under slight pressure and return to normal position when 50 the pressure is relieved. While I have shown my improvement as applied to the operation of a bell, only one stationary contact or a plurality of such contacts may be used.

The springs or yielding members, 5 and 55 6, are secured to suitable supports, 7 and 8, and means such as screws 9 are provided for adjusting such members. The springs 5 and 6 are connected to one pole of a battery, 10, which has its opposite pole connected to the 60 finger, 1, and a bell or other device, 11, is included in this circuit. A condenser, 12, or resistance, 13, or both, may be connected in shunt across the fixed and movable contacts.

It has been found experimentally that the 65 sparking and welding is due to the chattering which occurs when the movable contact touches the fixed contact. If however the parts carrying the fixed contact or contacts, or the finger carrying the movable 70 contact or contacts, or both such parts, be given the proper elasticity, such chattering when one contact touches the other will be avoided. Any elasticity or flexibility will not attain the desired object, but the proper 75 elasticity must be attained empirically, when the vibrations will be damped and thus sparking avoided. It will also be noted that by means of the screw 9 the tension of the arm 5 may be varied and this will vary the 80 period of vibration, so that the swing of the arms 5 and 1 may be made to coincide, which will effect a further decrease in chattering.

In case sparking and welding should occur, provision is made by making the contacts in the form of segments of spheres, for the rupture of such weld. Since the centers of motion of the arms are widely separated, the contacts in swinging will rub or roll one 90 on the other, thereby exerting such a leverage as will easily break any weld which may be formed.

It has been determined in a series of experiments with electrical contacts, that almost all metal contacts deteriorate in time when the pressure of one contact on the other is very slight. For example the resistance of silver or platinum contacts will run up to thousands of ohms in a few days 100 or hours. I have ascertained that contacts made of any alloy of platinum and iridium, preferably an alloy containing 5% or 10% of ididium will not deteriorate, and the resistance will not rise materially if at all 105 even when the contacts are pressed together very light, the pressure being of the order of one tenth of a milligram. This discovery

of the benefit derived by the use of this alloy bears no relation to my previous discovery that the high temperature due to arcing in induction coils, did not deteriorate contacts formed of platinum iridium. In the present case the good results are due to the fact that thin high resisting coatings or films will not form on platinum iridium contacts, even when there is not any heating from sparking. The arrangement of the spherical contacts on the yielding supports is further advantageous as when the movable contact bears against the other contact, both will move slightly in the same direction and there will be a rolling and a rubbing movement of one contact on the other tending to remove or break down any resisting film.

I claim herein as my invention:

20 1. An electrical contact device compris-

ing a plurality of contact members mounted respectively on resilient and upon resilient and pivoted supports, said members being of rounded form, whereby in making contact the members both slide and rotate in 25 contact with each other, substantially as described.

2. An electrical contact device comprising electrodes made of platinum iridium of general spherical form and mountings for 30 said electrodes in the form of pivoted and resilient arms, whereby to prevent sparking.

In testimony whereof, I have hereunto set my hand and seal, the 12th day of March A. D. 1906.

REGINALD A. FESSENDEN. [L. S.]
